UNITED STATES PATENT OFFICE.

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK.

DESIGN FOR AN ARM FOR ELECTRIC-LIGHT FIXTURES.

Application filed April 27, 1927. Serial No. 21,750. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for Arms for Electric-Light Fixtures, of which the following is a specification, reference being had to the accompanying drawing, forming part thereof.

In said drawing:

Figure 1 is a developed front elevation of

an arm for electric light fixtures showing my new design.

Figure 2 is a side elevation of the same, showing by broken lines the development on which Figure 1 is based, the solid line portion indicating the normal appearance of the finished article.

I claim:

The ornamental design for an arm for electric light fixtures, as shown.

CHARLES W. LOGAN.
